J. H. STALEY

WRECKING CRANE

Filed July 20, 1925

UNITED STATES PATENT OFFICE.

JOSEPH H. STALEY, OF COLUMBUS, INDIANA, ASSIGNOR TO NATIONAL STANDARD COMPANY, OF NILES, MICHIGAN.

WRECKING CRANE.

Application filed July 20, 1925. Serial No. 44,888.

This invention relates to improvements in wrecking cranes.

The main object of this invention is to provide an improved wrecking crane adapted to be mounted on a motor vehicle which is simple and economical in structure and one in which the boom may be easily adjusted to meet varying conditions.

Objects pertaining to details and economies of construction and operation of my invention will definitely appear from the detailed description to follow.

I accomplish the objects of my invention by the devices and means described in the following specification. The invention is clearly defined and pointed out in the claim.

A structure embodying the features of my invention is clearly illustrated in the accompanying drawing forming a part of this application, in which:

Fig. I is a perspective view of my improved wrecking crane.

Fig. II is a side elevation with the boom shown in one of its adjusted positions by full lines and in another position by dotted lines.

Fig. III is a fragmentary plan view.

Similar numerals of reference indicate similar parts in all of the views.

Referring to the drawing, I provide a frame adapted to be mounted upon the bed of a truck or the like and comprising base pieces 1, cross pieces 2 mounted on the base pieces to project at one end as at 3, uprights 4, a top 5, and suitable braces 6. The winch 7 is mounted upon this frame and has a gear 8 on its spindle, the driving pinion 9 being mounted on the frame to mesh with the gear 8.

The crank 10 is engageable with the stud 11 of the pinion or with the stud 12 of the gear 8 so that the drum may be rapidly turned when no particular power is required.

A holding pawl 13 coacting with the gear 8 is provided and a screw 14 is provided to lock the pawl in engagement.

The boom comprises a pair of angle iron side members 15 which are mounted on the pivots 16 on the projecting ends of the frame members 2. The coupling bracket and spacing member 17 is secured between the outer ends of the members 15 and has holes 18 therein for the attachment of the tackle. The tackle is designated generally by the numeral 19.

The supporting struts 20 are made up of telescoping sections, each section having a loop 21 at its inner end slidably embracing the coacting section. The struts have holes 22 therein with which the bolts or pins 23 may be selectively engaged so that the elevation of the boom may be varied within its scope as indicated by dotted lines in Fig. II.

To accomplish this it is only necessary to remove the bolts, the boom being supported or elevated by the tackle chain, if desired, and reinsert the bolts at the desired point. This adjustment can be quickly made and with comparatively little effort.

Having thus described my invention, what I claim as new and desire to secure by Letters Patent is:

The combination of a frame, a boom pivotally mounted on said frame, a tackle carried by said boom, a strut connecting said boom to said frame and comprising a pair of sections connected to the boom and frame, each section having a slide loop embracing the coacting section, one of the sections having a series of holes therein, and a pin selectively engageable with said holes for adjustably supporting the boom.

In witness whereof I have hereunto set my hand.

JOSEPH H. STALEY.
